MERCANDISE DISPLAY HANGER

Carl A. Fowler, Wichita, Kans.

Application April 12, 1941, Serial No. 388,231

3 Claims. (Cl. 211—45)

My invention relates to hangers for displaying merchandise such as rugs and like articles that are of considerable size and should be hung straight and with no wrinkles for best results in displaying the rug. In view of this, the object of my invention is to provide a hanger that will support the rug at comparatively close points across the width of the rug to avoid wrinkling of the rug.

A further object is to provide a hanger of the kind mentioned in which the rug may be easily and quickly attached and detached to the hanger.

A still further object is to provide a hanger of the kind mentioned that is provided with supporting elements that may be detached and attached both from the rug or the hanger so that the rug may be easily and quickly taken from the hanger and replaced thereon again.

Another object is to provide a hanger of the kind mentioned in which the supporting elements may be easily and readily detached from the hanger and mounted on or attached to the rug while the rug is lying on the floor or platform, or on a pile of rugs etc., and then the supporting elements may be mounted on the hanger to support the rug in a straight and vertical position.

Also another object is to provide a hanger of the kind mentioned that is provided with suitable means by which the hanger may be hung up or supported.

Still another object is to provide a hanger of the kind mentioned that is light and yet strong, and one that is cheap and easy to make, and one that is compact and adapted to be closely packed or stocked in a small space for shipment or storage.

These and other objects will be more fully described as this description progresses.

Now referring to the accompanying drawing:

Fig. 1 is a side view of what is probably the preferred form of the invention, a rug being carried by the hanger for purposes of illustration.

Fig. 2 is a top plan view of the hanger as shown in Fig. 1.

Fig. 3 is an enlarged detail end view of the hanger and rug supported thereby as shown in Fig. 1.

Fig. 4 is an enlarged detail side view of one of the ends of the hanger as shown in Fig. 1, the supporting clamp being removed for convenience of illustration.

Fig. 5 is a perspective view of a modified form of the hanger.

Fig. 6 is a perspective view of still another

modified form of the hanger in which the supporting elements are detachable from the hanger.

Similar numerals of reference designate the same parts through the several figures of the drawing.

In Figures 1 to 4 inclusive is shown what is probably the preferred form of the hanger, and in which is shown a heavy stringer wire or rod 10. At the central portion of the wire 10 is an inverted U-shaped wire 11, the ends of the legs of which are welded to the heavy wire 10 at the points 12 and 12a. At 13 is a truss wire the central portion of which is welded at the points 13a and 13b to the upper portion of the legs of the inverted U-shaped wire 11. The outer ends of the truss wire 13 are welded to the stringer wire or rod 11 at the points 13c and 13d adjacent the ends of the stringer wire or rod 10.

The hanger is provided with a hook element 14, the leg of which is welded at the points 15 and 16 to the central point of the inverted U-shaped element 11 and the truss wire 13.

Adjacent each end of the stringer wire or rod 10 are other identical inverted U-shaped elements 17 and 18 so as to form a hanger in the form of a King truss.

The supporting elements employed in this hanger are spring actuated clamp elements A, B and C, each of which is identical in structure.

The clamps A, B and C comprise a pair of duplicate opposing clamp portions 18a and 19 having upwardly extending operating wing elements 20 and 21. At the upper corners of the clamp portions 18a and 19 is an inwardly and then upwardly turned portions 22 and 23, and between the upwardly turned portions 23—23 is positioned a ball 24. Over the upturned portions 23—23 is a split circular shaped spring 25 the split ends of which engage the upturned portions 23—23 below the ball 24 so as to press the lower ends of the clamp elements 18a and 19 toward each other so as to clamp against and hold a rug 26 that may be placed therebetween.

Now by pressing the operating wing elements

20 and 21 toward each other the clamp elements 18a and 19 will be separated and the clamp A, B or C may be passed downwardly over the stringer wire or rod 10 in such a manner that the inverted U-shaped elements 17 or 18 will be positioned intermediate the springs 25—25 and the operating wings 20 and 21 and the inwardly turned portions 22 will rest on the stringer wire or rod 10 to support the clamps A, B or C. The inverted U-shaped elements 17 and 18 serve to station the clamps A and C on the ends of the

stringer wire or rod 10. The clamp B is positioned over and on the stringer wire or rod 10 in the same manner as the clamps A and C except that there is no inverted U-shaped element such as 17 or 18, but the clamp B is positioned between the legs of the inverted U-shaped element 11 which serve to station the clamp B in the central portion of the stringer wire or rod 10.

In Fig. 5 is shown a modified form of the hanger in which the stringer wire or rod 10 and the truss wire 13 and their assembly are identical to that shown in Fig. 1. The inverted U-shaped element 11a is made a little longer than that in Fig. 1 so as to form a loop 27 that serves the same purpose as the hook 14 in Fig. 1. The legs 11b are welded to the stringer wire or rod 10 and the truss wire the same as in Fig. 1. The stringer wire or rod 10 is provided with a series of sharp pointed spikes 28 that are directed upwardly and the butt ends of which are welded to the stringer wire or rod 10 so that a rug or other article may be hooked on the spikes 28 to support the article for display purposes.

In Fig. 6 is shown still another modification of the hanger in which the characteristic elements, the stringer wire or rod 10, truss wire 13, and the inverted U-shaped element 11c appear in the usual form and assembly. The ends of the stringer wire or rod 10 are turned upwardly as at 10x for reasons that will later be made obvious.

On the stringer wire or rod 10 is a series of S-shaped elements 29, one end of which is hooked over the stringer wire or rod 10 and the other end is sharpened so that a rug 26a may be pressed against the sharp end of the S-shaped elements so that the sharp points will pierce the rug so as to support the rug.

These S-shaped supporting elements may be easily and readily unhooked and removed from the stringer wire or rod 10. The sharp points of S-shaped elements may be hooked into the edge

of the rug while the rug is lying down and then the edge of the rug may be picked up and the S-shaped supporting elements 29 may be hooked over the stringer wire or rod 10 to support the rug 26a for display purposes.

While this hanger is designed primarily for hanging rugs for display purposes it is obvious that other articles such as piece goods, curtains and draperies and the like may be hung in a similar manner as the rugs for display purposes.

Such other modifications of my display hanger may be employed without departing from the spirit and intention of my invention. Now having fully shown and described my invention, what I claim is:

1. In a display hanger, comprising a wire frame, said frame having a stringer element that is supported by an inverted U-shaped element that is attached to the central portion of the stringer, a truss wire, the central portion of said truss wire being attached to the U-shaped element at a spaced distance above the stringer, the outer ends of said truss wire being attached to the stringer at points adjacent the ends of the stringer, and means formed in said frame for the support thereof, and means carried on said stringer for supporting articles.
2. In a display hanger, comprising a wire frame as defined in claim 1, said means for supporting articles being detachable from the stringer, said U-shaped element and other means on said stringer serving for stationing the said means for supporting articles.
3. In a display hanger, comprising a wire frame as defined in claim 1, said means for supporting articles being detachable from the stringer, said U-shaped element and other means on said stringer serving for stationing the said means for supporting articles, said means for supporting articles being spring actuated clamp devices.

CARL A. FOWLER.
